MECHANISM FOR ACTUATING THREAD TWISTING MEANS IN LOOMS

Filed Aug. 5, 1950

UNITED STATES PATENT OFFICE

2,676,618

MECHANISM FOR ACTUATING THREAD
TWISTING MEANS IN LOOMS

Erwin Pfarrwaller, Winterthur, Switzerland

Application August 5, 1950, Serial No. 177,787

6 Claims. (Cl. 139—54)

1

The present invention relates to an improved mechanism for actuating shedding cards and more particularly thread twisting means in looms for weaving.

The present application is a continuation-in-part of my co-pending application, Serial No. 12,948, filed March 4, 1948, which matured on July 8, 1952, into Patent No. 2,602,470.

It is an object of the invention to provide a mechanism for twisting warp threads in a loom for weaving by means of cards preferably having the configuration of rings with teeth on their circumferences which mesh with teeth of pinions which are rotated for actuating the cards. The present invention is particularly directed toward an improved driving mechanism for operating the aforesaid pinions to produce a pre-determined pattern of motions of the twisting rings.

The mechanism according to the invention comprises a shaft which is continuously rotated, preferably by the same source of power which operates the loom, cams having a plurality of individual active surface portions and being preferably exchangeably mounted on said shaft for producing the desired pattern of movement of the pinions and twisting rings, and operating means comprising cam followers engaging said cams and means connected with said cam followers and operatively connected with said pinions for moving the twisting rings in consecutive steps in accordance with the configuration of said cams. The aforementioned operating means preferably comprise a bellcrank lever-like member having a cam follower on each arm, said followers individually engaging the surfaces of a pair of like cams fixed on the aforementioned shaft in offset relation, and having a toothed surface on one arm engaging a pinion which is concentrically fixed to a gear wheel having teeth meshing with those of one of said pinions. The same pair of cams may be engaged by a second bellcrank lever which operates a second card disc through a second train of gears. Instead of providing two followers and two cams, each lever may have only one follower actuated by one cam, the cam being in the form of a groove receiving the follower or the follower may be pressed to the cam by the action of a spring connected with the lever and a stationary part of the loom. Such arrangements are conventional and their use is no departure from the scope of the present invention.

The mechanism according to the invention does not require means for translating the continuous rotation of a shaft, which may be ro-

2

tated by the loom drive, into an intermittent rotation of another shaft, although it may be modified to embody such means.

The cams preferably have surface portions between motion producing portions for suspending motion of the twisting means between successive actuations during desired periods of time.

The mechanism according to the invention is primarily for the purpose of twisting adjacent warp threads for binding weft threads, for example, at the edge of a fabric for producing a border. According to the design of the cams, the direction of twist may be reversed after each or a plurality of twists and, by interposing circular cam portions concentric with the axis of rotation of the cams between motion producing cam portions, operation of the twisting means can be suspended after each twist for a pre-determined duration. By proper design of the cams, this duration may, for example, after a desired number of twisting operations, be so great as to permit several weft insertions before making the next twist. By using appropriately shaped cams, a great variety of binding patterns can be obtained.

Further and other objects of the present invention will be hereinafter set forth in the accompanying specification and claims, and are shown in the drawings which, by way of illustration, show what I now consider to be preferred embodiments of the invention.

In the drawings:

Fig. 1 is a diagrammatic side elevation of a loom provided with a warp thread twisting mechanism according to the invention, but not showing the actuating means for the twisting mechanism.

Fig. 2 is a large scale side view, partly in section, of a mechanism according to the invention for actuating the twisting discs or rings;

Fig. 3 is a view in axial direction of a pair of cams forming part of the mechanism according to Fig. 2;

Fig. 4 is a diagrammatic showing of warp threads twisted about weft threads in a pattern produced by the cams shown in Fig. 3;

Fig. 5 is a view in axial direction of a pair of cams shaped differently from those shown in Fig. 3 for producing the pattern illustrated in Fig. 6;

Fig. 7 is a large scale view of a portion of one cam of the pair shown in Fig. 5;

Fig. 8 is a view in axial direction of a further modification of a cam pair for producing the pattern shown in Fig. 9.

Like parts are designated by like numerals in all figures of the drawings.

As shown in Fig. 1, the warp threads 7 move from warp beam 6 over a tensioning beam 20 where they separate to form an upper shed 21 and a lower shed 22, through eyes 24 of the heddles 18, and reed 25 to the apex 26 of the shed where they form the fabric 9 by interlacing with the weft threads 18. The fabric passes over a guide beam 27 and is then wound on a fabric beam 8.

Binding threads 28 and 29 move from spools 30 and 31 over the tensioning beam 20, individually through eyes 33 and 34 of a twisting ring 35, through the reed 25, and to the apex 26 of the shed, wherefrom they are wound, intertwined with fabric 9, on the beam 8.

The twisting rings 35 are supported in a frame 37. The rings are provided with teeth 38 and individually engage the teeth of pinions 39 and 40 which are keyed to shafts 41 and 42, respectively.

Fig. 2 illustrates a mechanism according to the invention for actuating the shafts 41 and 42 for producing the desired warp thread twisting pattern. Elbow or bellcrank levers 150 and 151, each having two arms, are positively oscillated about stationary pins 154 and 155, respectively, in the direction of double arrows 156, 157 by means of substantially circular cams 200 and 201 which are eccentrically mounted on shaft 145 and respectively engaged by rollers 165 and 166 on lever 150 and rollers 167 and 168 on lever 151. The oscillating movement of levers 150 and 151 is transferred by the toothed end portions 158, and 159, respectively, of the upright arms of the levers to double tooth wheels 160, 161 and 162, 163, respectively, and therefrom to pinions 121 and 122, respectively, on shafts 41 and 42. Shaft 145 may be driven intermittently in the direction of arrow 123 by a Geneva gear as shown in Patent No. 2,602,470. Shaft 145 may also be driven continuously, for example by the loom drive, which also drives the picking mechanism.

In the operating position shown in Fig. 2, lever 151 changes its movement from that indicated by arrow 169 to that of arrow 170 whereby the rotation of shaft 42 is reversed from arrow 171 to 172. Lever 150 moves in the direction of arrow 173 and shaft 41 rotates in the direction of arrow 174. Due to the relatively displaced positions of levers 150 and 151 reversal of rotation of shafts 41 and 42 does not occur at the same time.

If shaft 145 is driven continuously in the same direction of rotation, cam discs 200 and 201 must be provided with active cam surfaces composed of a plurality of individual curve portions. Figures 3, 5, 8 illustrate three differently shaped cam pairs for producing different twisting patterns. The individual cam portions which produce actuations of the twisting discs or rings are separated in Figures 3, 5, 7, 8 by radial lines *a* to *n*. The mechanism is at a standstill whenever the cam followers 165, 166 and 167, 168 reach a portion of the cam surface adjacent to the intersection with one of said radial lines because the cam surface is cylindrical concentrically with the rotation axis of the cam at such intersections and the elbow levers 150, 151 are not oscillated on their fulcrums 154, 155, respectively, under such conditions. The duration of the standstill periods depends on the length of the arc of the cylindrical cam portions. After the cam followers have reached an end of a cylindrical cam portion, the elbow levers 150 and 151 make par-

tial swings, depending on the length of the cam portion between two radial lines and the gear wheels 160, 161 and 162, 163 are rotated and effect rotation of shafts 41 and 42, respectively.

With a configuration of the cam discs 200 and 201 as shown in Fig. 3, the card discs 35 are rotated through 180° when shaft 145 rotates through an angle between any two consecutive radii *a* to *n*.

Fig. 4 is a diagram indicating the twisting pattern produced by the cams shown in Fig. 3. Twisting is reversed after six actuations of a twisting ring, when an elbow lever is actuated by a cam portion of smallest radial extent, as at radius *a*, and by a cam portion of greatest radius, as at *g*. At these points, direction of the swinging direction of the elbow levers is reversed. The surface of the cam traversing radial lines *a*, *b*, *c*, *d*, *e*, *f*, *g* is symmetrical to the surface traversing lines *a*, *m*, *k*, *i*, *h*, *g*.

When using cams as shown in Fig. 3, two warp threads are twisted about one another and, if the operation of the twisting mechanism is appropriately coordinated with that of the picking mechanism of the loom, about a weft thread at each angular movement of shaft 145 from one radial line to the next following radial line.

By using cam discs of a configuration illustrated in Fig. 5 and designated by numerals 202 and 203, a twisting pattern will be obtained as shown diagrammatically in Fig. 6. In this pattern, twisting is suspended while the cam shaft 145 moves from radius *c* to radius *b* and from radius *i* to radius *h* and, since the speed of shaft 145 is coordinated with that of the picking mechanism, two weft threads 18 will be bound between two consecutive twists of the warp threads. Fig. 7 illustrates a portion of cam disc 202 on a larger scale. When roller 165 abuts the arcuate surface 206 of disc 202 at radius *f*, lever 150 remains at rest until the roller rides up on the cam surface 208 between points 207 and 209, causing clockwise movement of lever 150. A cylindrical cam surface portion 210 begins at point 209 and extends to point 211 symmetrically to radius *g*. This cylindrical surface suspends movement of lever 150 and actuation of the card disc associated therewith. A descending portion 212 of the cam curve begins at point 211 and continues at point 213 into a circular portion 214 at radius *h* which portion ends at point 215 beyond radius *i*. This extended circular portion suspends actuation of a twisting ring during the period when shaft 145 moves through the angle enclosed by radii *h* and *i*. Thereafter roller 165 rides down on cam curve portion 216 until it reaches point 217 ahead at radius *k* thereby causing a second partial swing of the lever actuated by the cam, this second partial swing having the same direction as the first partial swing caused by the cam portion 212. After a standstill along circular cam curve portion 218, the roller rides down further, or inward as seen in Fig. 2, along cam portion 220 between points 219 and 221, causing the actuated lever to make a third partial swing in the same direction as the first two partial swings. The same happens between radii *m* and *n* and *n* and *a*, as seen in Fig. 5. The twisting rings are rotated through 180° upon each partial swing of the respective levers, the rotation being not reversed as long as a cam follower rides on the cam portions indicated by radii *a* to *g*. The swing direction of the lever is reversed at radius *g* and continues, stepwise, in the reversed direction when the cam follower

rides along the cam portions confined between radii g , h , i , k , m , n , and a . At a the swing motion of the lever is again reversed.

By exchange and use of different cam discs, any pattern of intertwining may be produced. For example, by using cams as shown in Fig. 8, two weft threads may be inserted between twists of different directions. This is diagrammatically illustrated in Fig. 9, where the twist is reversed not at g , as in Figs. 4 and 6, but at i . According to this pattern, two weft threads are intertwined between two consecutive twists, and there are only four twists between changes of direction of twist. If only one weft thread were bound in between two consecutive twists, the warp threads would be twisted eight times in one direction before they were twisted in the opposite direction. With the cams shown in Fig. 8, an interval is permitted between consecutive twists in the same, as well as in the opposite, direction. It will be noted that in the pattern according to Fig. 4, the direction of twist is reversed after six twists.

Though the provision of cylindrical portions at the intersections of the cam curve with the radii a to n is desirable, the device would operate also if no such portions were arranged between the active cam surface portions. The eyes 33 and 34 of the twist rings hold the shed open long enough to permit insertion of a weft thread also if no special provisions are made for extending the time during which the shed is wide open.

A considerable advantage of the present invention is that it adapts the weave construction of the twisted threads to the weave construction of the fabric. The distance of the weft thread in the small twisted selvage must be chosen in accordance with the character of the fabric, especially for loose woven patterns like tulle, in that the edge is not to be stiffer than the fabric. A further advantage is that by adapting the weave constructions of both fabric and selvage the length of the twisted warp threads is kept the same as the length of the other warp threads, so that the twisted threads do not need special bobbins but may be wound on the warp beam.

While I believe the above described embodiments of my invention to be preferred embodiments, I wish it to be understood that I do not desire to be limited to the exact details of method, design and construction shown and described, for obvious modifications will occur to a person skilled in the art.

I claim:

1. In a loom, the combination of a continuously rotating shaft, thread twisting means, operating means connecting said shaft and said twisting means for rotating the twisting means stepwise in either direction; said operating means comprising a bellcrank lever, a cam follower fixed to each arm of said lever, pairs of substantially like cam members fixed on said shaft, one cam member of each pair engaging one cam follower and the other cam member engaging the other cam follower, said cam members having a series of active cam surface portions actuating said lever

in consecutive steps, and a mechanism interconnecting said lever and said twisting means for transmitting the motions of said lever to said twisting means.

5 2. A mechanism for actuating thread twisting means in looms comprising a plurality of rotatable twisting members, a continuously rotating shaft, a pair of cams fixed on said shaft, each cam having a series of individual consecutively effective cam surface portions, a lever for each cam, said levers being engaged by said cams and individually stepwisely actuated by said surface portions to make partial swings upon rotation of the cams through an angle substantially corresponding to one of said surface portions, and a plurality of motion transmitting means individually interconnecting said levers and said members for rotation of the latter upon each partial swing of the respective lever and reversing the direction of rotation of said members upon reversal of the swinging direction of said levers.

10 3. A mechanism as defined in claim 2, said levers having the configuration of bellcranks individually engaging said cams with one arm, said motion transmitting means being individually connected to the other arms of said bellcrank levers.

15 4. A mechanism as defined in claim 2, said cams having cylindrical surface portions concentric with the rotation axis of the cams and individually disposed between two consecutive cam surface portions for suspending actuation of the respective levers between actuations by said cam surface portions.

20 5. A mechanism as defined in claim 2, said cams individually having two symmetrically shaped and diametrically opposed sides, each side having a series of consecutively acting individual surface portions.

25 6. A mechanism for actuating a rotatable thread guiding member in a loom, said mechanism comprising a shaft rotating continuously in one direction, substantially circular cam means fixed eccentrically on said shaft, a lever actuated by said cam means, said cam means having a series of individual active cam portions for causing said lever to make a partial swing upon rotation of said cam means through an angle substantially corresponding to one of said surface portions, and a motion transmitting means interconnecting said lever and said member for rotation of the latter upon each partial swing of said lever and reversing the direction of rotation of said member upon reversal of the 30 swinging direction of said lever.
